RAILING UNIT AND RAILING POST

Louis Blum, Pittsburgh, Pa., assignor to Blumcraft of
Pittsburgh, Pittsburgh, Pa., a firm

Filed Jan. 29, 1959, Ser. No. 54,387

Term of patent 14 years

(Cl. D13—7)

FIG. 1.

FIG. 2.

FIG. 3.

FIG. 1 is a side elevational view of a railing structure showing my new design for a railing unit;

FIG. 2 is a side elevational view of a modified form of a railing structure showing my new design as a railing unit as used on a stairway;

FIG. 3 is a perspective view of a railing structure showing my new design in the form of a railing post and its connectors.

The dominant features of my design are shown in solid lines.

I claim:

The ornamental design for a railing structure, as shown and described.
